OF BROOKLYN, NEW YORK, A CORPORATION OF NEW YORK

CAP-DELIVERY MECHANISM

Application filed July 2, 1927. Serial No. 203,004.

This invention relates to counting and feeding mechanism and particularly to a machine for counting out and feeding to a container, a predetermined number of such individual articles as crown caps and the like.

When articles are sold in packages, it is now customary to pack in the containers therefor, a definite number of the individual articles. Difficulty is experienced in packing precisely the same number in different containers if the articles are measured by weighing them. By means of my improved machine, however, the number of crown caps or like articles to be inserted in the package can be counted with accuracy and the carton or container therefor can be quickly and easily filled invariably with the correct number of the articles by unskilled and inexperienced help.

The various objects of my invention will be clear from the description which follows and from the drawings, in which,

Fig. 1 is a side view of my improved mechanism and the support for the container to be filled, part of the mechanism being broken away for clearness.

Fig. 2 is a front view of the same.

Fig. 3 is an enlarged vertical section of the chute for the caps, and of the stop mechanism, part of the chute being omitted.

Fig. 4 is a horizontal section of the cap chute, and

Fig. 5 is a bottom view of a series of chutes, showing how said chutes may be arranged to double or triple the usual number of caps fed to the container.

In the practical embodiment of my invention, the crown caps 10 are fed to a hopper 11 of the usual type, which is operatively connected to a suitable agitator 12. The agitator serves to align and to feed the caps in a single row and in the proper positions to a chute 13, and may be operated in the usual manner, as by means of the belt 14 driven by a suitable source of power, not shown, and rotating the pulley 15, mounted on the agitator shaft.

The chute 13 is formed with the cap passage 16 and may consist of the rear plate 17, the spacers 18 and the front plates 19, all suit-

ably secured together as by means of the screws 20. Below the lower end 21 of the chute is arranged a table 54 of a height convenient to the operator. The chute is made of sufficient length to align therein at least 55 the number of crown caps required to be inserted in the smallest carton 22. It will be understood that the chute is substantially upright so that the caps may pass out therefrom by gravity when allowed to do so. 60

Stop means are provided to maintain the caps in the chute until a minimum predetermined number has accumulated therein, and to release an unvarying number of said caps to allow said caps to drop into a carton 22 at 65 the will of the operator. Said stop means includes a stop finger 23 adapted to engage a cap near the upper end of the chute and a stop hook 24 adapted to enter the cap passage 16 and to be interposed between the lowermost cap in the chute and the end of the chute, together with suitable mechanism for 70 operating the finger and the stop. The stop 24 is formed with a hook end 25 sufficiently thin to pass between the front plates 19 of 75 the chute and into engagement with the front surface of the rear plate 17. The bearing brackets 26 secured to the chute as by means of suitable screws 27 serve as supports for the rock shaft 28, on which the stop 24 is 80 supported. The lever 29 is also secured to the rock shaft 28 and is connected at one end with the link rod 30 and at its other end to the connecting link 31, a tension spring 32 acting on the lever 29 to maintain the stop 24 normally in operative position. The lower end 85 of the link rod 30 is secured to the treadle 33, pivoted at 34, so that foot pressure on the treadle pulls the link rod 30 and the lever 29 downwardly against the action of the spring 32 and moves the hook 25 out of the chute, thereby releasing the row of caps and allowing them to drop out of the chute. 90

The upper end 35 of the upright connecting link 31 is secured to the crank 36, which is 95 mounted on the shaft 37, rotatably supported in the bearings 38. On said shaft 37 is fixed the crank arm 39 terminating in the plunger 40 which is inserted into the bore 41 of the finger 23. A pin 42 on said plunger 40 oper- 100

ates in the slot 43 of said finger and serves to prevent the separation of said finger from said plunger. Excessive movement of the crank arm 39 is taken up by the yieldable compression spring 44 interposed between the ends of the bore 41 and the plunger 40, whereby undue pressure on the cap engaged by the finger 23 is prevented and undue stress on the mechanism avoided. The crank arm 39 and the finger 23 secured thereto may be mounted on the shaft 37 to project in substantially the reverse direction to that in which the stop 24 projects from its shaft 28, so that when the treadle 33 is operated to withdraw the stop 24 from the chute to release the row of caps, the finger 23 is caused simultaneously to enter the chute and engage the cap adjacent thereto. Similarly, when the treadle is released, and the hook end 25 of the stop 24 enters the chute under the influence of the spring 32, and stops the discharge of the caps from the chute) the finger 23 is withdrawn and allows the caps to fall into contact with each other in a row, filling up and accumulating in the chute above the stop 24. If the chute is designed for a four dozen carton, the finger 23 and the stop 24 are spaced apart a distance equal to slightly more than the combined diameters of forty-eight caps. The forty-ninth cap in the row counting up from the bottom, is normally free of the finger 23, the row being supported by the stop 24.

On the operation of the treadle, the stop 24 being withdrawn, the finger 23 engages the forty-ninth cap in the row and prevents that cap together with the caps thereabove from passing through the chute and into the carton. After the carton has been filled, the treadle 33 is released, and the operation reversed, whereby the row of caps accumulate above the stop 24 ready for delivery into the next carton.

It will be understood that, if desired, the crank arm 39 and the stop 24 may be mounted on the same or corresponding sides of their respective shafts and that the relative reversal in operation may be effected by securing the lower end of the connecting link 31 to the left end of the lever 29 as viewed in Fig. 1 in a manner which will be obvious.

If the cartons are to be filled with larger numbers of caps, such as eight or twelve dozen, a multiplicity of identical chutes and connecting mechanisms may be provided. In Fig. 2, I have illustrated two additional chutes 46 and 47 arranged at an angle so that their respective lower extremities 49 and 50 are spaced apart a distance less than the size of the carton adapted to hold a gross of caps. The shafts 28 on the aligned chutes 49 and 50 may be removably coupled together by means of any suitable shaft coupling and an additional removable rod link 30 connected from the treadle 33 to the lever 29

of either of the chutes 49 and 50. The operator, to fill the largest size carton, need then only press the treadle which, with the connection just described, operates all the chutes in unison. To fill the carton with eight dozen caps, the link rod 30 to one of the chutes need merely be disconnected, and the treadle operatively connected to only two of the shafts 28 as above described, whereby operation of the treadle releases the four dozen caps in each of the two chutes simultaneously.

It will be understood that where a multiplicity of chutes is used, the chutes may be advantageously emptied in succession, when filling even the smaller size carton, since time is thereby allowed for the emptied chute to be again filled before its turn comes to be emptied.

It will further be understood that I do not intend to be limited to the specific structure shown and described herein, as it will be obvious that various changes may be made falling within the spirit and scope of my invention and within the range of equivalents afforded by the appended claims.

I claim:

1. In mechanism of the character described, a substantially upright chute having a cap passage therethrough, and a pair of stops in predetermined spaced relation each separately pivoted to said chute and adapted to enter said passage alternately, one of said stops having a yieldable spring pressed finger thereon including a hollow slotted cylinder, a pin on the stop entering the slot of the cylinder, and a compression spring in the cylinder and engaging the end of the stop.

2. In mechanism of the character described, a substantially upright chute having a cap passage therethrough, means for delivering a single cap at a time to said chute, a yieldable spring pressed stop pivoted near the upper end of said chute adapted to enter said passage for accumulating caps thereabove, a hook stop pivoted near the lower end of said chute, and means including a spring acting in one direction and a treadle acting in the opposite direction for oscillating said stops simultaneously in opposite directions whereby one of said stops enters said passage when the other of said stops is withdrawn therefrom.

3. In mechanism of the character described, a substantially upright chute having a cap passage therethrough, means for delivering a single cap at a time to said chute, a stop near the upper end of said chute adapted to enter said passage for accumulating caps thereabove, a similar stop near the lower end of said chute, and means for oscillating said stops simultaneously in opposite directions whereby one of said stops enters said passage when the other of said stops is withdrawn therefrom including a treadle, a

spring pulled lever operatively connected to one of said stops and to said treadle, a crank operatively connected to the other of said stops, and a link connecting said lever and 5 said crank.

4. In mechanism of the character described, a carton supporting table, a chute, means for accumulating a row of articles in said chute, and means for releasing a predetermined 10 multiplicity of articles from the remainder of the row for ejection by gravity from said chute and into a carton on said table including a spring-pulled treadle, a pair of spaced stops operatively connected together, a 15 member for oscillating one of said stops, and a link rod directly connecting the treadle to the member.

5. In mechanism of the character described, a chute having a cap passage therethrough, 20 and means adapted to engage a cap in said passage and adapted to enter said chute for alternately stopping and allowing movement of the caps in said passage comprising a pivoted member and means for rocking said 25 member, a hollow finger mounted for yielding limited movement on the end of said member, a spring interposed between the member and the finger inside of said finger, and a slot and pin connection between the member and finger 30 for limiting the relative movement thereof.

6. In mechanism of the character described, a cap chute having a cap passage therethrough, and a second passage meeting the cap passage and extending to the outside of 35 the chute, said chute being of greater length than that necessary to receive in a single row, the predetermined number of caps to be inserted into a carton, a pair of stops adapted to pass through said second passage into 40 the cap passage alternately, said stops being spaced apart a distance substantially equal to the combined diameters of said predetermined number of caps, and means for simultaneously rocking said stops in opposite 45 directions, including a foot treadle, a crank for each of the stops, and a link rod directly connecting the treadle to one of the cranks.

7. In mechanism of the character described, a cap chute having a cap passage 50 therethrough of sufficient width to allow caps normally to fall therethrough in a single row, and means for releasing a predetermined number of caps in said passage whereby said caps drop out of said chute, the length of said 55 chute being greater than the distance occupied by said predetermined number of caps, said means including a pair of independently pivoted stops, a treadle, a pivoted oscillatory member for each of said stops, and a 60 rod connecting the treadle to one of the members.

8. In mechanism of the character described, a chute having an outlet at the lower end thereof, an oscillatory stop for allowing caps 65 to accumulate in said chute, a shaft on which

said stop is mounted, a second oscillatory stop in predetermined spaced relation to the first mentioned stop and mounted for oscillation in the opposite direction to that in which said first stop is oscillated whereby a predetermined number of caps may be arranged in 70 said chute between said stops, a second shaft on which the second stop is mounted, independent of the first shaft, and means for operating said shafts whereby only one of said 75 stops at a time enters the chute, said means including a treadle, a crank for each of said shafts, a link connecting said cranks, and a rod connecting the treadle to one of said cranks.
